Primary Examiner — Patricia Palasik(74) *Attorney, Agent, or Firm* — Brooks Kushman P.C.(57) **CLAIM**

The ornamental design for a bar clamp for an automation fixture, as shown and described.

DESCRIPTION

FIG. 1 is a perspective view of the bar clamp for an automation fixture;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines are for illustrative purposes only and form no part of the claimed design.
